UNITED STATES PATENT OFFICE

134,773

DESIGN FOR A TOY MACHINE GUN

Robert C. Flynt and Ursal K. Butler,
Winston Salem, N. C.

Application September 28, 1942, Serial No. 108,346

Term of patent 3½ years

To all whom it may concern:

Be it known that we, Robert C. Flynt and Ursal K. Butler, both citizens of the United States, and both residing at Winston Salem, in the county of Forsyth and State of North Carolina, have invented a new, original, and ornamental Design for a Toy Machine Gun, of which the following is a specification, reference being had to the accompanying drawings, forming part thereof.

Fig. 1 is a side elevational view of a toy machine gun showing our new design;

Fig. 2 is a top plan view;

Fig. 3 is a rear elevational view;

Fig. 4 is a side elevational view thereof with the supports shown in Figs. 1, 2 and 3 removed;

Fig. 5 is a top plan view of the design as shown in Fig. 4;

Fig. 6 is a rear elevational view; and

Fig. 7 is a front elevational view thereof.

We claim:

The ornamental design for a toy machine gun, as shown.

ROBERT C. FLYNT.
URSAL K. BUTLER.
